United States Patent Office.

S. A. MUEL SCOTT, OF YANE, OHIO.

Letters Patent No. 98,195, dated December 21, 1869.

IMPROVEMENT IN FARM-GATES.

The Schedule referred to in these Letters Patent and making part of the same.

To all whom it may concern:

Be it known that I, SAMUEL SCOTT, of Yane, in the county of Logan, and State of Ohio, have invented certain new and useful Improvements in Farm-Gates; and I do hereby declare that the following is a full, clear, and exact description thereof, reference being had to the accompanying drawings, making part of this specification, and to the letters of reference marked thereon.

Like letters indicate like parts, wherever they occur.

To enable others skilled in the art to construct and use my invention, I will proceed to describe it.

My invention relates to farm-gates; and

It consists in a novel manner of constructing the same, so that when closed, the upper hinge may be relieved of all strain and weight, and thus prevent the swaying or leaning of the gate-post; and, also, in so constructing the hinges, that during the winter-season, the gate may be adjusted to swing over the snow.

In the drawing—

Figure 1 is a front view of my gate, closed and fastened, and the upper hinge relieved;

Figure 2 is a front view of the same, unfastened, and ready to be swung open; and

Figure 3 is an inside face view of the front gate-post.

A is the gate;

B, the back gate-post; and

C is the front gate-post.

The gate A, I construct in the ordinary manner, and across its front, place a long bar or lever, D, bolting one end to the back end of the gate, and allowing its opposite end to project past the front end of the gate, as shown in figs. 1 and 2.

Near the rear end of the lever D, I attach to it an arm or plate, e; and near the front end, I connect an upright slotted handle, a, playing on the stud b on the gate, as clearly shown in figs. 1 and 2.

To the rear gate-post B, instead of the ordinary hinges, I attach two elongated bows or staples, f and f, and through the latter, near its upper end, I pass a pin or key, g, as shown in figs. 1 and 2.

The gate A, I connect to the lower staple f, by means of an ordinary hinge, h, and to the upper staple, by a link, i, attached at its inner end to the arm e of lever D.

By this arrangement, it will be seen that if the front end of the lever D is depressed, the arm e will pull upon the link i, and draw the upper rear corner of the gate toward the staple, and, consequently, elevate its front end. As the lever is raised, the link is released, and the front end of the gate allowed to drop down.

To the front bar of the gate, I attach a block, m, under which the end of the lever is engaged, when the front end of the gate is to be held up.

To the inner face of the post C, I secure two blocks, j, having their outer ends bevelled, and provided in their upper edges with notches n, fig. 3.

To close the gate, the lever D is depressed, to throw up the front end, and the gate swung to; the lever is then thrown up, and the projecting ends of the bars will drop into the notches n, thus securely fastening the gate, and, at the same time, relieving the link i, and throwing the entire weight upon hinge h and blocks j, as shown in fig. 1.

To open the gate, the lever is again depressed, when the link is brought into action, and the front end raised, disengaging the bars from blocks j, and the gate left free to turn.

The handle a is for operating the lever from the outside of the gate.

In this manner, I relieve the upper end of the gate-post from all strain, except when the gate is open, and thus prevent the swaying or leaning of the post, and consequent dragging of the gate upon the ground, as happens where the post is subject to a constant strain, and, at the same time, produce a strong and simple locking-device.

During the winter-season, when it is desired to have the gate swing above the snow, or in pastures, where small stock are to be allowed passage, to the exclusion of cattle, and other large stock, I raise the gate, and place the key g below the hinge h, thus supporting the gate in that position.

When the gate is adjusted, as described, another and lower pair of bars engage in the notches n, but the gate operates otherwise, as before.

It is obvious that my lever-arrangement may be used in connection with ordinary hinges, if desired, instead of with the staples described, as the hinges have nothing to do with the operation of the other parts.

Having thus described my invention,
What I claim is—

1. The combination of the lever D, provided with its handle a and arm e, with the link i and staple e, as set forth.

2. The gate A, provided with the projections on its front end, resting on the catches j, when the upper hinge is made adjustable, substantially as described.

SAMUEL SCOTT.
